PAPER CONTAINER HOLDER

Eula O. Baker, Pontiac, Mich.

Application February 28, 1950, Serial No. 146,733

5 Claims. (Cl. 294—31)

1

This invention relates to holders for milk bottles and the like, and more particularly to a holder for a paper container.

An object of this invention is to provide a holder for a paper container that may be safely and securely attached to the container so that the container may be more easily handled.

Treated paper containers for milk and the like of half gallon size have become readily available and are used extensively. These containers when full are quite heavy and are quite unwieldy and difficult to handle.

It is therefore another object of this invention to provide a handle for a paper container which may be so placed as to readily enable the contents of the container to be poured therefrom.

A yet further object of the invention is to provide means for engaging the creased edges of the paper container and to provide means for insuring this engagement.

Still further objects of the invention reside in the provision of a holder for either of the two principal types of paper containers now generally used, that is, the containers with the "half pitch top" and the containers with the "flat top."

Yet other objects reside in the provision of a holder for a paper container that is strong, durable, highly efficient in operation, simple in construction and manufacture, capable of being readily and easily attached to and removed from a paper container, easy to manufacture, capable of being made from a variety of divergent materials, and which is relatively inexpensive.

These, together with the various ancillary objects of the invention which will become apparent as the following description proceeds, are attained by this paper container holder, a preferred embodiment of which has been illustrated in the accompanying drawings, by way of example only, wherein:

Figure 1 is a perspective view showing a preferred form of the invention in operative placement on a "half pitch top" container;

Figure 2 is a view taken substantially along the line 2—2 in Figure 1;

Figure 3 is a partial end elevational view of the invention; and

Figure 4 is a perspective view showing another preferred form of the invention for use with a "flat top" container.

With continuing reference to the accompanying drawings wherein like reference numerals designate similar parts throughout the various views, reference numeral 10 generally designates a "half pitch top" container which is illustrated

2

in phantom to more clearly show the manner in which the first preferred form of the invention can be secured to this form of container.

The container holder is preferably made from a light metal such as aluminum or aluminum alloys but may be readily made from any other metal or from suitable molded plastic material. The device consists of a base 12, preferably square in shape, which may be readily positioned over the container in an encompassing relationship therewith. Riveted, welded or otherwise secured to the base 12 is a handle member 14 which is riveted or otherwise secured to a first creased edge engaging member 16. The member 16 is formed with a hook portion 18 at one end and an arcuate bifurcated portion 20 at its other end. A second creased edge engaging member 22 having a central portion formed with notches 24 therein is so positioned that the bifurcated portion 20 of the first member 16 will engage the second member 22 in the notches 24. Furthermore the member 22 is provided with a hook portion 26 for engagement with a creased edge of the container 10. Formed in the members 16 and 22 are apertures 28 and 30 respectively in which there is engaged a spring 32 which continuously urges the hook portions 18 and 26 into engagement with the creased edges 33 of the container 10. When it is desired to remove the holder from the container 10 it is merely necessary to press the finger engageable portion 34 of the member 22 thus tensioning the spring and separating the hook portions 18 and 20 thus releasing the holder from the creased edge portions 33.

Another form of the invention is shown in Figure 4 wherein a container 40 of a "flat top" design is shown. In this form of the container unlike the form of the container shown in Figure 1, the pouring spout is in the corner of the container making it highly desirable to provide the handle portion 42 of the holder at a point diagonally opposed to the pouring spout of the container 40. The base 44 of this form of holder is similar to the base 12. However, the handle 42 is welded or otherwise secured to the base 44 at one of the corners thereof rather than at a midportion of a side. The handle is secured at its other end by spot welding, riveting, or any other suitable means to the first member 46 of this form of the invention which is provided with a hook portion 48 for engagement with the creased top edge of the "flat top" container 40. The hook portion 48 is so designed as to permit a grasping of the creased edge on either edge of the container adjacent a corner. A recess 50 is

55

therefore formed in the hooked portion to permit the corner to extend without. A member 46 is further provided with a bifurcated end portion 52 and an aperture 54 to facilitate engagement by the spring 56 which is otherwise secured to the second member 58 within the aperture 60. Notches 62 formed in the second member 58 provide means for pivotally mounting the second member 58 relative to the first member 46. The hook portion 64 of the second member 58 is also provided with a recess 66 therein so as to permit the corner of the container 40 to extend without. A further recess 68 is formed in the member 46 so as to permit the pouring spout of the container 40 to be more easily opened. Similar to the operation of the device shown in Figures 1, 2, 3, by merely pressing the finger engageable portion 70 downwardly the hook portions 64 and 48 will be separated permitting the removal or emplacement of the paper container holder.

Since from the foregoing the construction and advantages of this holder for paper containers are readily apparent, further description is believed to be unnecessary.

However, since numerous modifications will readily occur to those skilled in the art after a consideration of the foregoing specification and accompanying drawings, it is not intended to limit the invention to the precise embodiments shown and described, but all suitable modifications and equivalents may be readily resorted to falling within the scope of the appended claims.

Having described the invention, what is claimed as new is:

1. A paper container holder comprising means for encompassing the body of a paper container, a first member having a hooked end portion, a second member pivotally engaging said first member intermediate its ends, said second member having a hooked end portion means urging said hooked end portion of said first member toward said hooked end portion of said second member, and a handle terminally attached to said first recited means and said first member, said second recited means being disposed normal to said handle and adapted to extend across the top of the container, said second member having a lug thereon opposite said hooked end for biasing the hooked end of the second member away from the hooked end of the first member.

2. A paper container holder comprising means for encompassing the body of a paper container, a first member having a hooked end portion adapted to engage an upper corner edge of a paper container, a second member pivotally engaging said first member, said second member having a hooked end portion for engaging an opposed corner edge of a paper container, a spring terminally connected to said first and said second member urging said hooked end portion of said first member toward said hooked end portion of said second member to maintain engagement of said hooked end portions with the creased edges of a container, and a handle terminally attached to said means and said second member, said members together comprising means adapted to extend across the top of a paper container.

3. A paper container holder comprising means for encompassing the body of a paper container, a first member having a hooked end portion

adapted to engage an upper corner edge of a paper container and having a bifurcated end portion, a second member pivotally engaging said first member within said bifurcated end portion, said second member having a hooked end portion for engagement with an opposed corner edge of a paper container, a spring terminally connected to said first and said second member urging said hooked end portion of said first member toward said hooked end portion of said second member to maintain engagement of said hooked end portions with the creased edges of a container, a handle terminally attached to said means and said second member, said members together comprising means adapted to extend across the top of a paper container.

4. A paper container holder comprising means for encompassing the body of a paper container, a first member having a hooked end portion adapted to engage a creased edge of a paper container and having a bifurcated end portion, a second member having a notched central portion, said second member pivotally engaging said first member, said bifurcated end portion engaging said central portion within said notches, said second member having a hooked end portion for engagement with a creased edge of a paper container, a spring terminally connected to said first and said second member urging said hooked end portion of said first member toward said hooked end portion of said second member to maintain engagement of said hooked end portions with the creased edges of a container, and handle means terminally attached to the first and said second recited means.

5. A paper container holder comprising a base for encompassing the body of a paper container, a handle extending upwardly from said base and having a free end terminating remote from said base, a cross piece secured intermediate its ends to the free end of said handle and extending transversely thereof, one portion of said cross piece having an edge engaging hooked end, the other portion of said cross piece being inclined upwardly and having a bifurcated end, an end member pivotally secured intermediate its ends to said bifurcated end, one portion of said end member having a hook-shaped end disposed substantially opposite the hooked end of said cross piece, resilient means extending between said hook-shaped end portion of said end member and said upwardly inclined portion of said cross piece normally biasing said hook-shaped end portion toward said inclined portion, the other portion of said end member being a lug for manually biasing said one portion thereof in a direction opposite to its normally biased position.
